WAX POT FOR SHOE SEWING MACHINES

Frederick C. Jones, Norfolk, Va.

Application July 16, 1934, Serial No. 735,517

3 Claims. (Cl. 91—32)

This invention has reference to certain new and useful improvements in wax pots for shoe sewing machines and the object of the invention is to provide a pot of this character which is especially adapted for use on lockstitch sewing machines and which is characterized by simplicity of construction, facility of mounting, and the fact that the amount of wax in the pot may be at all times ascertained at a glance.

10 The invention together with its objects and advantages will be best understood from a study of the following description taken in connection with the accompanying drawings wherein:

Figure 1 is an elevation view of the wax pot.

15 Figure 2 is a view taken at right angles to Figure 1 and with certain of the parts shown in section.

Figure 3 is a top plan view of the wax pot assembly.

20 Figure 4 is a bottom plan view of the supporting bracket for the pot.

Figure 5 is a fragmentary sectional view through an eyelet equipped end of a guide plate.

25 Figure 6 is an elevational view of a thread guide and stripper and guide pulley assembly.

Figure 7 is a fragmentary sectional view through the body plate of the attaching bracket.

Referring to the drawings by reference numerals, it will be seen that the invention consists of a bracket 10, the same being in the form of a plate 11 having an attaching flange 12 integral therewith and provided in its edges with notches 13 whereby the bracket may be secured to any suitable part 14 of a lockstitch or other suitable type of shoe sewing machine through the medium of screws 15.

The plate 11 of the bracket is provided in its underface with a circular recess 16 provided with inwardly extending projections 17.

40 The wax pot proper is indicated by the reference numeral 18 and is in the form of a glass jar having a threaded neck 18 that fits into the recess 16 of the plate 11 with the threads of the neck engaging the projections 17 in a manner clearly shown in Figure 2 to secure the neck within the recess. The top of the jar 18 is substantially closed through the medium of a disk 19 of rubber or other suitable material clamped between the neck of the pot and the plate 11 as shown in Figure 2.

In the region of the recess 16, the plate 11 in the top thereof is provided with openings accommodating pins or reduced projections provided on the lower ends of thread guides and strippers 20 and 21 respectively.

The thread guide and stripper members 20 and 21 consist of externally threaded bodies having sockets in their upper ends accommodating therein stripper blocks 22 secured in position by apertured plugs 23, which are in turn secured in position through the medium of socket nuts 24 threaded onto the bodies or shells of the members 20 and 21. The nuts 24 are provided with suitable radial sockets 25 for the reception of a suitable tool in screwing the nuts onto the members 20 and 21 or removing the same therefrom.

The member 20 is secured in position through the medium of a bolt 26 that extends through a flange 26a formed integrally with the member 20 and which bolt and nut means also extends through the plate 11.

Associated with the member 21 is a pulley supporting bracket 27 which, as clearly shown in Figure 6 is provided with a base flange disposed under the flange 21a formed integral with the member 21, and extending through apertures in the base flange of the bracket 27, the flange 21a, and the bracket plate 11 is suitable bolt and nut means 28 for securing the members 21 and 27 in position on the plate 11 of the bracket. Suitably mounted on the bracket 27 is a guide pulley 29.

Disposed vertically within the pot 18 is a thread guide plate 30 that at its upper end is provided with an attaching flange whereby the bracket is secured in position through the medium of the aforementioned bolt and nut means 28. Adjacent its lower end the guide plate 30 is provided with eyelets 31 and 32.

In actual practice, a thread 33 leading from a suitable spool is passed down into the pot 18 through one of the openings 34 provided in the plate 11 of the bracket, and within the pot 18 said thread is trained through one of the eyelets, for example, the eyelet 31, the thread in passing upwardly through a suitable opening provided therefor in the bottom of the member 21, and also through the stripper 22, after which said thread is trained over the guide pulley 29, and from the pulley 29 the thread passes through the various directing devices and finally to the needle or other stitch forming mechanism.

Also in accordance with this invention, a second thread 35 is passed into the wax in the pot 18 through the other of the opening 34, and within the jar the second thread is trained through the other eyelet, in this instance, the eyelet 32, then through the guide member 20, the stripper associated therewith and thence over the various directing devices either to the needle or stitch 65

forming mechanism of a second sewing machine, or this second thread may be used solely for emergency purposes in case the first thread should break.

5 5. What is claimed is:

1. In combination, a wax pot having a threaded neck, a supporting bracket for the pot having an apertured plate-like portion constituting a cover and provided with a recess equipped with lugs adapted to be engaged by the threads of the neck for securing the pot to the bracket, the apertures in the bracket plate serving as openings for the thread, and guide means for the thread extending from the bracket into the wax pot, said guide means comprising a plate having an end secured to the bracket and a free end terminating within the wax pot and provided with eyelets for the passage of the thread therethrough, and thread guide and stripper members mounted on the bracket for the passage therethrough of the thread issuing from the wax pot, and a bracket associated with one of said thread guide and stripper members, a guide pulley journaled on the bracket and over which the thread passing through the said one guide and stripper member is trained.

2. A support for wax pots comprising a bracket for attachment to a sewing machine, said bracket including a lateral apertured plate constituting a cover and formed with a recess equipped with lugs on its lower side adapted to receive the threaded neck of a wax pot, the apertures in the plate serving as entrances for untreated thread, a guide means secured to the lower side of the

plate within the cavity and depending therefrom, said lateral plate further formed with a pair of openings, a combined apertured thread guide and stripper member one above the other mounted on top the lateral plate one in each opening, a lateral flange on one of the combination guide and stripper members, an upstanding bracket having an arm secured under the flange, and a guide pulley journaled on the upstanding bracket in alignment with the aperture 10 in the combination guide and stripper by which the upstanding bracket is secured.

3. In combination, a glass wax pot having a threaded neck, an angular supporting bracket having an upright leg adapted for connection to a sewing machine, the lateral leg of the bracket constituting a cover for the wax pot and provided with a recess in which the neck of the wax pot is removably seated, the walls of the recess equipped with lugs engageable with the threads on the neck of the wax pot for detachably securing the wax pot to the lateral leg of the bracket, said lateral leg of the bracket being apertured within the area defined by the cavity to permit threads to enter and leave the wax pot, apertured guide means secured to the lower face of the lateral leg within the cavity and depending into the wax pot, and an apertured gripping member secured to the upper face of the lateral leg within the area defined by the cavity with the aperture therein registering with the aperture in the lateral leg by which the thread leaves the wax pot.

25 30 FREDERICK C. JONES.
